ORE CONCENTRATING TABLE

Charles F. Hutchings, San Francisco, Calif.

Application November 7, 1934, Serial No. 751,839

5 Claims. (Cl. 208—441)

This invention relates to ore concentrators, and the objects of the invention are to provide an improved construction in magnetically vibrated concentrating tables whereby greater efficiency and effectiveness may be obtained, and in a simple rugged structure not liable to get out of order. Other features and advantages of the invention will appear in the following description and accompanying drawings.

10

The drawings

In the drawings Fig. 1 is a plan view of my improved concentrating table.

Fig. 2 is a side elevation of the machine.

Fig. 3 is a central cross section of the machine as seen from the line 3—3 of Fig. 1.

Fig. 4 is a cross section of the table only taken along the line 4—4 of Fig. 1.

Fig. 5 is a diagrammatic view of the magnetic 20 drive.

Fig. 6 is a flat plan of the contact wing plate of the rectifying commutator.

Brief description

25 My improved concentrator consists of a rifled oscillating doubly inclined table suspended or supported from a frame by means of double parallel ball-bearing bar construction at opposite long edges of the table, preferably on slanted or angularly disposed links or arms connecting the upper and lower bars, which provide for flexibility of oscillating movement with minimum of friction, all in combination with a double coil magnetic solenoid drive energized alternately to pull in 30 opposite directions, the change from one directional pull to the other being made from a point of neutrality in the energizing current, or the longitudinal axis of the sine curve of a low frequency A. C. current so as to obtain a quick building up of the operating energy in both directions to directly work in time with the rebound of the table against a pair of shock-absorbing springs. The slanted links or arms supporting the table for rapid oscillation are secured at opposite ends respectively to the upper and lower parallel bars, and which bars are in turn respectively rotatably mounted in ball bearings secured along the supporting frame above, and the opposite long edges of the table below, and all of which co- 35 operate to make it possible to rapidly vibrate a large heavy table without most of the energy being absorbed.

The table or platform

55 The table 1, which may be of any size, though

conveniently is about 4 x 10 feet, preferably constructed of wood for lightness, and covered with waterproof material such as a sheet of linoleum 2, is provided with a rail 3 along its lower edge to form a run-off water gutter for water and tailings 5 and over which rail the linoleum extends as shown in Fig. 4. A shorter rail 4 is also provided along the upper edge of the table. The table is flat and is suspended in a manner to tip slightly downward toward an observer of Fig. 1, as well as downward 10 toward the right-hand end of Fig. 1. A table of this size rigidly constructed will weigh about 75 to 100 pounds.

The riffles

Secured to the surface of the table is a series of 15 shallow riffles 5, preferably of metal, as aluminum. These riffles abut the rail 3 at their lower ends and extend transversely and angularly part way over the table at an angle of about 45° with their upper ends terminating on a line X—X running from about the center of the left-hand end of the table to a point just below the upper right-hand corner of the table. These riffles are preferably about 3/64ths of an inch thick by 1/4th inch wide and straight, and they are spaced about 1 1/2 or 2 inches apart. A second series of shorter riffles 6 of about 1/4th of an inch or less in thickness may be interposed in the first series and aligned with the upper ends thereof as shown, while at 7 and 8 at the extreme right-hand end of the table are 20 a pair of V-shaped deflectors arranged so as to guide tailings off below 7, concentrates between 7 and 8, and fine concentrates above 8. Considerable variation in shape and spacing of the riffles is permissible, but the arrangement shown 25 has produced exceptionally good results.

The frame

The frame of the machine is in two portions— 40 an upper and a lower portion. The upper portion 9 which includes T iron members 9', extending transversely above the table and from which the table is suspended, as will later be described. This upper frame is pivoted at 10 along its lower long edge to a lower or sub-frame 11 so that its angle of tilt with respect to the lower long edge may be 45 controlled, and to this end one or more screw jacks 12 are mounted along a longitudinal member 11' of the sub-frame in a manner to raise or 50 lower the upper edge of the upper frame, and in order to lock the upper frame at any point of adjustment fixed brackets 13 are provided on the sub-frame having slots as at 14 to pass a long clamping bolt or rod 15 provided with nuts 16 55

for clamping the brackets against the sides of the lower transverse members of the upper frame.

The lower portion or sub-frame 11 is slanted longitudinally downward toward the right-hand end as shown, and is pivotally supported at its upper end at 17 on legs 18 so that its angle of inclination can be varied. To adjust the sub-frame angle, the right-hand end is supported on one or more screw jacks 19 resting on a base 20 in 10 turn secured to a foundation or floor 21 and the lower end after raising or lowering is clamped firmly to legs 22 which are slotted as at 23 for passage of the clamping bolt 24.

Table suspension

15 The suspension of the table on its arms or links 31 is shown carried out by means of two pairs of parallel bars or shafts 25 and 26, the former being rotatably mounted in ball bearings 27 carried in 20 brackets 28 secured to the under sides of overhead T iron frame members 9', and the latter rotatably mounted in ball bearings 29 carried in boxes 30 secured along the upper and lower margins of the table and displaced laterally from the 25 upper bearings 27 a few inches so that the supporting links or arms 31 which join the upper and lower shafts will hang at an angle to the vertical substantially as shown in Fig. 3 so as to cause a slight upward throwing of the particles of ore and sand toward the upper margin of the table as the 30 same is rapidly vibrated in a transverse direction. The links or arms 31 are here shown as bolts or rods passing through both shafts, and with nuts on both sides to afford nice adjustment and locking in place, but of course may be otherwise attached. Also to be noted is that while I show the angular pivotal arms supporting the table from above, they may be below the table if desired as understood in the art providing the proper 40 angle is maintained to secure the upward throw or jumping of the material being treated. Shafts or bars 25 are preferably made of pipe to reduce weight. The links or rods firmly bolted through the parallel shafts form a rigid grid-like construction so they cannot twist out of parallelism, and 45 its combination with the ball bearings in the manner described produces a table of practically frictionless side movement.

Oscillatory drive

50 The table is rapidly vibrated or oscillated on its pivotal arms 31 by means of a powerful solenoid 32 provided with two separate spaced windings 33, 34 operating alternately on a single iron core 35 firmly riveted to or otherwise mounted on a bronze or brass rod 36 in turn mounted in plain or axially movable ball bearings 37 supported in brackets 38 fixed at opposite ends of the solenoid so that the core will be centered and free 60 to slide back and forth in the field windings. The solenoid assembly is all carried as a unit in a frame 39 firmly bolted to the side of upper frame 9. Threads are cut on both ends of the bronze rod 36 and wing nuts 46 and 47 are provided to 65 adjust the core in the magnetic field and to limit its throw as will later be explained. Rod 36 is firmly coupled at 40 to a smaller rod 41 which extends entirely across under the table 1 through openings in the table braces 1' and is threaded at 70 42 through a metal plate secured to one of them as at 42' and provided with a handwheel 43 at its outer end for adjusting the angle of table suspending links 31 by screwing the table either way on threads 42. Rod 41 may be locked in adjusted 75 position to the table frame 1' by means of a nut

44 threaded to the rod and provided with a long tubular neck or pipe collar 45. The adjustment of the table with respect to the links as just described does not alter the adjustment of the solenoid core 35 in its field windings as it simply revolves when the wheel is turned, and its longitudinal position is determined and limited in both directions by two pairs of large wing nuts 46, 47 threaded to rod 36 and which may be locked in any position along the rod so as to leave the desired 10 operating space between the inner nut of each pair and the frames 38 and 9 respectively, and in both of which spaces a heavy coiled compression spring 48, 49 surrounds the rod to function as a shock absorber. The adjustment of nuts 46 and 15 47 is to be such as to allow free play to the core and only bring the springs into contact with the frame stop just before the end of the desired stroke. By the adjustments 43, 44, 46 and 47, any desired stroke in one direction relative to the 20 other may be had.

Energizing of the magnets

The solenoid windings are energized alternately about $8\frac{1}{3}$ rd times a second in the manner indicated by reference to Fig. 5 wherein 50 is a two pole A. C. generator driven 500 r. p. m. and giving an alternating current of $8\frac{1}{3}$ cycles per second which is taken off by means of brushes 51, 52 on rings 53, 54 in conjunction with a 30 winged commutator or rectifier mounted on the generator shaft 56. This commutator is here shown as a cylinder with a wing-shaped conducting area 55 stepped in at opposite sides with insulating areas 55' and fitted with three 35 brushes 57, 58, 59, as indicated. Fig. 6 shows the cylindrical surface of the commutator as flattened out, while Fig. 5 shows diagrammatically the wiring from the brushes and slip rings and connections to the two coils, the arrangement being such as to open the circuit to one coil just before closing it to the other coil at the zero voltage point of the current curve, so that coil 33 will be energized by the half cycle 60 and coil 34 from the other half cycle 61 and thus each coil 40 will draw the core 35 toward its center in alternation with practically instantaneous reversals of power, each coil of the solenoid receiving a current pulsation at each revolution of the generator. A three-point condenser is preferably 45 connected to the wing commutator brushes as indicated at 62 to absorb current surge incident to magnet discharge. The strength of the bumper springs is carefully proportioned with respect to the weight of the table and frequency of the vibration. 50

With the above construction and electrical drive I am able to operate a ten foot table, weighing with its water and ore, about 90 pounds with less than 200 watts current consumption, and get a sharp kick to throw the ore particles upward with instant dropping and return of the table beneath them, which is vital to the success of a gold separator. 55

Nature of the vibratory movement

In adjusting the angle of the suspension links with the handwheel 43 the greater their lower ends slant in a direction away from the magnet, the more vigorous is the kick to the material on top of the table. The material moves in the 70 same direction that the links slant.

With the table, links and solenoid in position shown in Fig. 3, the links being slanted downwardly in the direction shown, the suspended weight of the table causes the table to swing for 75

ward or toward the solenoid and bring its weight against spring 49 leaving an open space 48' at the outer end of spring 48. The first electric pulsation is in coil 34 causing the core 35 to 5 push the table outward or toward the left. This movement closes space 48' and creates a like space at end of opposite spring 48 which is maintained until coil 34 dies and coil 33 is energized, and whereupon the reversal of the 10 direction of magnetic pull snaps the table back to its original position. During the fractional second of time elapsing during magnetic reversal there is an open space at spring 49 and for this instant there is nothing supporting the 15 weight of the table, and therefore when coil 33 takes hold, the gravity of the heavy unsupported table together with the sudden powerful pull of the magnet, gives the table an instantaneous snap back to its original position, closing the 20 gap at spring 49 and opening it at spring 48 again as shown in Fig. 3.

In further explanation of the vibratory movement, referring to Fig. 3, the first pulsation of current in coil 34 moves the table to the left. 25 the supporting links move in an arc which gives the table a lift as well as a lateral movement to the left, and this lifting of the table adds to the gravity of the material giving it more of a tendency to stick to the table surface and move with 30 it to the end of the magnetic stroke. The return movement, however, being in the nature of an instantaneous drop and side pull back to starting position, the material is, for an instant, left in suspension, and by the time it settles 35 again onto the table surface, the table has completed its return movement and the heavy particles settle to an advanced position on the table, or further away from the magnet. Thus the concentrate moves steadily upward over the 40 table in minute jumps, at a speed governed by the angularity of the links and the cycle speed.

The movement of light materials by means of carriers suspended on slanted links or arms is not new, but the application of this principle to 45 the substantial weight of a concentrating table with its accompanying load of ore and water, has not been successfully accomplished until the development of my invention which supplies to this principle new and unusual characteristics 50 of vibration as well as the necessary mechanical and electrical devices to attain the desired result.

Flow of materials

In operation of the machine, water is supplied by any convenient manner to give a uniform flow over the table from along the upper long edge and also from the left-hand end, and the table being adjusted for about a three-inch side tip and about a seven-inch end tip, gives a diagonal flow of water across the table of about 45°. 60

In the machine shown in the drawings the water is delivered in a thin sheet to the upper long margin of the table from a trough 63 slotted along one edge as at 64, supplied to the trough 65 from a pipe 66 arranged above the trough and provided with a series of downwardly directed pet cocks 68, while a similar branch pipe 67 extends across the upper end of the table to feed water to it in a manner controlled by the adjustment of the cocks. 70

The finely divided ore material in liquid condition with water is fed constantly to the table as from a pipe 68 near the left-hand end of the table to at once spread out over the surface due to the vibration and riffle action. 75

Effect of combination, water and vibration

Vibration causes agitation of both ore and water over the entire surface of the table, the lighter materials owing to greater bulk and less gravity have tendency to float with the water stream which flows rapidly over riffles at right angles. This light material is stirred to the surface where table "kick" has minimum effect and is carried downward to lower levels and to the tailings. 10

On the other hand the concentrates are heavy and of less bulk. They are lifted only a minute distance from the table surface by vibration and fall back quickly, consequently the heavy particles are more subject to table kick than to the water flow. The result is a persistent movement of concentrate over the linoleum surface toward the upper edge of the table; the riffles help shield the concentrates against the flow of water; there is less water movement between the riffles and close to the linoleum than on the surface of the water. 15 20

The magnetic vibration is of such characteristic that the concentrates stratify within a few seconds after falling upon the table. 25

Net result of operation is a visible ribbon of black concentrate traveling from head end of table, moving successively over top end of each riffle, finally delivering in several grades at tail end at 69 and 70. The tailings are carried off the same end but lower portion 71. 30

In considering my invention as above described it will be manifest that various modifications can be made without departing from the spirit of the invention and scope of the appended claims. 35

I therefore claim:—

1. In apparatus of the character described, a substantially horizontally disposed concentrating table, a frame, a plurality of rigid table supporting links pivotally connected at opposite ends to the table and frame respectively, said links being similarly inclined at an angle relative to a vertical plane extending longitudinally of the table, a solenoid having a slidably core connected to said table for vibrating the same laterally, a pair of adjacent field coils surrounding the core, means for automatically energizing said coils alternately in rapid succession whereby the table is vibrated laterally, means for varying the length of movement of the core in either direction. 40 45

2. In a construction as defined in claim 1, means for varying the degree of inclination of the links relative to said vertical plane. 50

3. In apparatus of the character described, a substantially horizontally disposed concentrating table, a frame, a plurality of rigid table supporting links pivotally connected at opposite ends to the table and frame respectively, said links being similarly inclined at an angle relative to a vertical plane extending longitudinally of the table, a solenoid connected to the table arranged and adapted to vibrate said table in a direction substantially normal to the longitudinal axis of the table, means for varying the stroke of the solenoid and means for varying the degree of inclination of said links relative to said vertical plane. 60 65

4. In a construction as defined in claim 3, said last mentioned means being carried by the table.

5. In apparatus of the character described, an imperforate, elongated, concentrating table having a head end for receiving valuable bearing material and a tail end for discharge of tailings thereover, an upstanding ledge along one side of the table extending between the head and tail end thereof, a plurality of riffle bars on the table extending diagonally thereacross from the ledge in a 70 75

direction toward the tail end, means for feeding water onto the table along the head end and side opposite the ledge, a stationary supporting frame, said table being disposed generally horizontally but elevated at the head end and side opposite the ledge relative to the tail end and side of the ledge respectively whereby water flowing over the table will be relatively deep along the ledge and of progressively less depth from the ledge toward the side opposite the ledge and whereby the riffles will coat with the ledge to cause pools of substantially non-flowing water along the riffles, supporting means connecting the table to said frame mount-

ing said table for oscillating generally vertically and horizontally in a vertical plane at substantially right angles to the table and in an arcuate path of travel confined to one side only of a vertical line extending through the axis of the arc and from a lowermost position spaced from said line, lifting means arranged and adapted to intermittently move said table upwardly in said arcuate path of travel and to release said table at the upper end of the path for falling solely by gravity 10 to the lowermost position free of the influence of said lifting means.

CHARLES F. HUTCHINGS.
